(57) **CLAIM**

The ornamental design for a device for cutting small food items, as shown and described.

DESCRIPTION

FIG. 1 is a perspective view of a device for cutting small food items;

FIG. 2 is a front elevation view thereof;

FIG. 3 is a right side elevation view thereof;

FIG. 4 is a rear elevation view thereof;

FIG. 5 is a top plan view thereof;

FIG. 6 is a left side elevation view thereof; and,

FIG. 7 is a top plan view thereof.

The broken lines which illustrate openings and internal components of the device for cutting small food items do not form a part of the claimed design.
